UNITED STATES PATENT OFFICE.

JAMES J. HENNESSY, OF NEW YORK, N. Y.

LOCOMOTIVE JOURNAL LUBRICATOR.

1,412,740.

Specification of Letters Patent. Patented Apr. 11, 1922.

Application filed July 19, 1920. Serial No. 397,341.

To all whom it may concern:

Be it known that I, JAMES J. HENNESSY, a citizen of the United States, residing at New York city, New York, have invented a certain new and useful Improvement in Locomotive Journal Lubricators, of which the following is a full, clear, and exact description, such as will enable others skilled in the art to which it appertains to make and use the same, reference being had to the accompanying drawings, forming part of this specification.

My invention relates generally to lubricating devices and more particularly to a locomotive journal lubricator of the general type disclosed in my copending applications, Serial Number 250,045, filed August 15, 1918; Serial Number 352,098, filed January 17, 1920, and Serial Number 397,342, filed

20 July 19, 1920.

The principal objects of my present invention are, to generally improve upon and simplify the construction of the lubricating devices disclosed in the applications afore-

25 said; to provide a relatively simple lubricating device that is entirely automatic in operation; to provide a lubricating device which, by virtue of its relatively simple construction, may be easily and cheaply produced; 30 to construct a lubricating device so that its parts may be readily assembled or taken apart, thereby greatly simplifying and facilitating inspection, adjustment, and repairs; and, further, to provide a device that 35 is positive in action and effective to a high degree in performing its intended functions.

With the foregoing and other objects in view, my invention consists in certain novel features of construction and arrangement of 40 parts, hereinafter more fully described and claimed, and illustrated in the accompanying drawings, in which—

Figure 1 is a vertical section taken lengthwise through the center of a locomotive journal lubricator of my improved construction.

Figure 2 is a vertical section taken approximately on the line 2—2 of Figure 1.

Figure 3 is a cross section taken approximately on the line 3—3 of Figure 1.

Figure 4 is a plan view of my improved lubricating device.

Figure 5 is an enlarged detail section taken approximately on the line 5—5 of 55 Figure 4.

Figure 6 is an enlarged detail section

taken approximately on the line 6—6 of Figure 4.

Figure 7 is a detail section of the self-adjusting push rod that is utilized for actuating the plunger of the liquid lubricant pump.

Referring by numerals to the accompanying drawings, which illustrate a practical embodiment of my invention, 10 designates the main body of the lubricating device, the same being preferably formed of cast or pressed metal and in the form of an open-topped receptacle, the side walls of which extend a substantial distance above the end walls and the upper edges of the latter being curved in order to conform to the radius of the journal to which the lubricator is applied. This construction of the body or container 10 permits the same to partially enclose the lower portion of a locomotive journal or the like and said body or housing can be secured in any suitable manner to parts of the locomotive frame that are adjacent to the journal.

Depending from the outer portion of the body or container 10 is a casing 11, the chamber 12 within which serves as a well for containing the supply of liquid lubricant that is circulated through the device. Centrally arranged within the lower portion of body or container 10 is a longitudinally disposed rod 13, the end portions of which are detachably arranged upon the end walls of the container, and formed integral with or fixed to this rod is a vertically disposed tubular member 14 that extends downward into the liquid lubricant well 12. The lower end of this tubular member 14 and its upper end are open and formed through the wall thereof near its lower end are ports 15 which admit liquid lubricant from the well into the chamber within said tubular member.

Arranged for reciprocatory movement within the tubular member 14 is a tubular plunger 16 provided adjacent to its lower end with an internally arranged valve seat 17 upon which is adapted to rest a valve 18. This valve is held upon its seat by a compression spring 19, the upper end of the latter bearing against the underside of a perforated screw plug 20, that is seated in the upper end of plunger 16. Formed in the outer surface of plunger 16 are oppositely disposed notches 21 and loosely arranged therein are the forked ends 22 of a horizontally disposed arm of a bell crank 23.

Suitable openings 24 are formed in the tubular member 14 for the accommodation of the plunger engaging arms 22. Bell crank 23 is fulcrumed upon a pin 25 that is seated 5 in suitable webs or brackets 26 that are formed integral with rod 13 and tubular member 14, and the upper portion of the vertical arm of this bell crank is bifurcated to form a pair of arms 23^a that engage in 10 suitable notches that are formed in a plunger operating rod 27. This rod is arranged for reciprocatory movement in an axially disposed bore 28 that is formed in that portion of the rod 13 between tubular member 15 14 and the inner end of the body of the container 10, and positioned on the outer end of said rod 27 or that end which projects beyond the inner end wall of container 10 is a head or disk 29 that is adapted to be engaged by the face of the adjacent wheel hub.

The inward movement of rod 27 is yieldingly resisted by a compression spring 30 that is arranged upon the inner end of said rod and bears against a shoulder thereupon 25 and against an oppositely disposed shoulder formed within rod 13. Positioned within the container 10 and above the rod 13 and parts associated therewith is an open-topped waste pan or container 37, the central portion 30 of the bottom of which is bent upward throughout its length to form a longitudinally disposed inverted U-shaped portion 38 that lies immediately over and partially encloses the rod 13. Formed in this inverted 35 U-shaped portion is a suitably located aperture 39 that accommodates the upper end of tubular member 14.

Removably secured to the end walls of the pan or container 37 are relatively thin blocks 40 of wood or analogous material, the upper edges thereof being curved to conform to the radius of the journal to which the lubricating device is applied, and these wooden blocks perform the functions of combined 45 dust guards and packing members to restrict the outward flow of liquid lubricant from the ends of the waste pan or container. The pan or container 37 is yieldingly held against the underside of the journal with which the lubricator is associated by means of a spring 41, the central portion of which is bent into inverted U-shape so as to extend upwardly over the rod 13 and the end portions of said 50 spring being extended laterally and bent 55 upwardly to form resilient arms which engage beneath the side portions of the pan or receptacle. (See Fig. 2.)

In Figure 7 I have illustrated an arrangement whereby the plunger actuating push rod is rendered self-adjusting so that it will yield under abnormal lengthwise movement and thus prevent the breakage of some part of the pumping mechanism. This particular construction is described in detail and

claimed in my copending application Serial 65 Number 397,342, filed July 19, 1920.

When my improved lubricating device is properly installed for use, sufficient waste or like fibrous material is placed in pan or container 37 to make direct contact with the underside of the journal and a suitable supply of liquid lubricant is placed in well 12 of container 10.

The axle having the journal to which the device is applied always has a certain 75 amount of lateral movement during operation, and as the wheel carried by said axle moves toward the lubricating device, the face of the wheel hub will bear against head or disk 29, thereby moving the same and the 80 push rod 27 a slight distance lengthwise through rod 13. As a result of this movement of the push rod, bell crank 23 will be actuated to move pump plunger 16 downwardly in tubular member 14, and as the 85 lower end of said plunger passes ports 15, a portion of the liquid lubricant trapped in the lower portion of the chamber in member 14 will be forced upwardly past check valve 18 and a corresponding amount of liquid 90 lubricant will be forced from the open upper end of tubular member 14, it being understood that the chamber within the plunger 16 and the chamber in the upper portion 95 of the tubular member 14 are filled with liquid lubricant after the device has been in operation for a short time.

The liquid lubricant thus forced from the upper end of tubular member 14 will pass directly into the body of waste within the 100 pan or container 37, and thus the body of waste is maintained in a saturated condition and the liquid lubricant will be applied directly to the underside of the journal with which the waste is in constant contact. 105

As the wheel hub recedes or moves away from head or disk 29, compression spring 30 will act to return the parts of the pumping mechanism to their normal positions and the operations just described will be 110 repeated as the wheel hub again moves toward the lubricating device. As a result of these continued operations, small quantities of oil are intermittently delivered into the body of waste within the pan or container 27, thereby keeping the latter saturated and affording continuous lubrication for the journal with which the device is associated. Any oil which may leak outwardly past the blocks or plates of wood 115 40 will pass downwardly into the container 10 and into the liquid lubricant well that depends from said container.

The waste pan or container is yieldingly held against the underside of the journal 120 by spring 41 and as said pan is formed entirely separate from the member 13 and associated parts, it can be readily detached

and removed from the container 10 for the purposes of inspection, adjustment or repairs. Likewise, the member 13 and parts carried thereby can be easily and quickly removed from the container 10.

A lubricating device of my improved construction is comparatively simple, may be easily and cheaply manufactured, can be advantageously employed in connection 10 with practically all existing types of locomotive journal boxes, is wholly automatic in operation, and is very effective in pumping liquid lubricant to the waste or like fibrous material that makes direct contact with the 15 journal of the axle, thereby insuring constant lubrication for that portion of the journal that engages the brass or journal bearing.

It will be readily understood that minor 20 changes in the size, form and construction of the various parts of my improved lubricating device can be made and substituted for those herein shown and described, without departing from the spirit of my invention, the scope of which is set forth in the 25 appended claims.

I claim as my invention:

1. In a journal lubricator, a container, 30 a waste receptacle positioned in said container, a vertically reciprocating pump within said container, means adapted to be actuated by the lateral movement of the journal for operating said pump, to feed liquid lubricant from the container into the 35 waste receptacle.

2. In a journal lubricator, a container, a waste receptacle positioned in said container, a pump within said container, means adapted to be actuated by the lateral movement 40 of the journal for operating said pump to feed liquid lubricant from the container into the waste receptacle, and yielding pressure means supporting said waste receptacle.

45 3. In a journal lubricator, a container provided with a liquid lubricant well, a vertical open-topped tubular member extending into said well, a tubular plunger arranged for vertical reciprocatory movement within said tubular member, a check valve within said tubular plunger, and means adapted to be actuated by the lateral movement of a part of the journal with which the lubricator is associated for imparting reciprocatory movement to said plunger.

4. In a journal lubricator, a lubricant reservoir, a pump having a fixed position therein, a waste receptacle movable relative to 60 said pump, said pump being adapted to supply lubricant to said receptacle irrespective of the movement of the latter.

5. In a journal lubricator, a container provided with a liquid lubricant well, a vertical 65 open-topped tubular member extending into

said well, a tubular plunger arranged for reciprocatory movement within said tubular member, a check valve within said tubular plunger, means adapted to be actuated by the lateral movement of a part of the journal 70 with which the lubricator is associated for imparting vertically reciprocatory movement to said plunger, a waste receptacle removably positioned within said container, and packing plates carried by the ends of 75 said waste receptacle and adapted to engage the journal with which the device is associated.

6. In a journal lubricator, a container provided with a liquid lubricant well, an open-topped tubular member extending into said well, a tubular plunger arranged for reciprocatory movement within said tubular member, a check valve within said tubular plunger, means adapted to be actuated by 80 the lateral movement of a part of the journal with which the lubricator is associated for imparting reciprocity movement to said plunger, a waste receptacle removably positioned within said container, and yielding 85 pressure means arranged beneath the waste receptacle for forcing the same upwardly into contact with the journal with which the device is associated.

7. In a journal lubricator, a waste receptacle adapted to be positioned beneath a journal, means for yieldingly maintaining said receptacle in engagement with the journal, a pump fixedly positioned beneath said waste receptacle, a push rod for actuating in 100 one direction said pump, which push rod is adapted to be actuated by the lateral movement of the journal with which the lubricator is associated and a spring for operating said rod in the opposite direction, said pump 105 when actuated being adapted to supply lubricant to said receptacle.

8. In a journal lubricator, a waste receptacle adapted to be positioned beneath a journal, yielding pressure means for maintaining 110 said receptacle in engagement with the journal, a pump positioned beneath said waste receptacle, a spring-held push rod for actuating said pump, which push rod is adapted to be actuated by the lateral movement of the 115 journal with which the lubricator is associated, and said pump and waste receptacle being separable from each other and independently removable from the container.

9. In a journal lubricator, a container, a 120 spring supported waste receptacle removably positioned in said container, and a liquid lubricant pump removably positioned within the container below said waste receptacle.

10. In a journal lubricator, a container, a spring supported waste receptacle removably positioned in said container, and a liquid lubricant pump removably positioned within the container below said waste receptacle. 125 130

- tacle, said pump including a tubular plunger and a check valve therein.
11. In a journal lubricator, a container, a spring supported waste receptacle removably positioned in said container, a liquid lubricant pump removably positioned within the container below said waste receptacle, said pump including a vertically operating plunger and a check valve therein, and a pump actuating push rod that is adapted to be operated by the lateral movement of a part of the journal with which the lubricator is associated.
12. In a journal lubricator, a lubricant reservoir, a pump including a vertically operated plunger, and means actuated by the horizontal movement of a journal member relative to the lubricator for actuating said pump.
13. In a journal lubricator, a lubricant reservoir, a pump including a vertically operated plunger adapted to be actuated by the horizontal movement of a journal member with which the lubricator is assembled.
14. In a journal lubricator, a waste receptacle adapted to be positioned beneath a journal, wooden packing plates on the ends of said waste receptacle, a pump for delivering liquid lubricant into said waste receptacle, and means adapted to be actuated by the lateral movement of a part of the journal with which the device is associated for operating said pump.
15. In a journal lubricator, a container, a spring supported waste receptacle removably positioned in said container, wooden packing plates carried by the ends of said waste receptacle, and a pump for delivering liquid lubricant from said container into said waste receptacle.
16. In a journal lubricator, a lubricant reservoir, a pump including a vertically operated plunger, and a fulcrumed bell crank having a horizontal arm engaging said plunger and a vertical arm adapted to be operated by horizontal movement of a journal member relative to the lubricator.
17. In a journal lubricator, a lubricant reservoir, a pump including a vertically operated plunger, a slidably mounted horizontal push rod, and a fulcrumed bell crank having one arm engaged by said rod and the other arm engaging said plunger.
18. In a journal lubricator, a lubricant reservoir, a pump including a vertically operated plunger, a horizontal push rod slidably mounted, one end of said rod being engageable by a journal member, yielding means pushing said rod into position to be so engaged, and a fulcrumed bell crank having one arm engaged by said rod and the other engaging said plunger.

In testimony whereof I hereunto affix my signature this ninth day of July, 1920.

JAS. J. HENNESSY.
